By

C. J. HAZLITT;
Robert W. Fauble,

Attorney,

Inventor:

UNITED STATES PATENT OFFICE

CLARK J. HAZLITT, OF NEAR RICHMOND, INDIANA

ANGLER PACKET

Application filed March 24, 1931. Serial No. 524,899.

The object of my present invention, broadly speaking, is the provision of an angler packet of novel construction and arrangement, by the employment of which a fisherman will be able to carry his hooks in a neat and compact form whereby the hooks will not become damaged in transport or the angler become injured by the hooks; and further, to provide a neat and compact 10 portmonnaie of novel arrangement, and which can be manufactured and sold at a comparatively low price.

And, finally, my object is to provide a new article of manufacture which combines 15 with its utilitarian qualities, means for carrying and displaying advertising matter thereon, whereby the advertising matter will be preserved indefinitely.

Other minor objects and particular advantages of this invention will suggest themselves in the course of the following description relating thereto.

The preferred means for carrying out the principles of my invention in a practical 25 and an efficient manner is shown in the accompanying drawings, in which—Figure 1 is a plan view of my complete assembly opened out, showing the inside thereof. Figure 2 is the same as Fig. 1, except that 30 the suspensory device is opened and the hooks omitted therefrom.

Figure 3 is a longitudinal central section of the device, as taken on the line 3—3 of Fig. 2. Figure 4 is a central cross section 35 of the device, as taken on the line 4—4 of Fig. 2. And Figure 5 is a perspective view of the complete packet in closed condition.

Similar indices denote like parts throughout the several views.

40 In order that the construction, arrangement, and the advantages of my invention may be more fully understood and appreciated, I will now take up a description thereof, in which I will set forth the same as 45 fully and as comprehensively as I may.

The case or main portion of my device is formed by a single piece of suitable material, such as leather or the like, which is folded on the lines A and B, whereby the 50 case is divided into three distinct parts

integral with each other, and comprising the central body portion 1; the inner flap portion 2, and the outer flap portion 3.

Numerical 4 denotes the hanger, the same being formed of a single piece of sheet 55 metal, doubled flat upon itself, forming a tubular portion 4' at the fold. Said hanger is located horizontally in the center of the body portion 1; at the upper edge of the body portion, by means of the rivets 5, 60 which rivets pass through the double thickness of the hanger 4, with the two edges of the hanger 4 located substantially even with the upper edge of the body 1.

In connection with said hanger I employ a 65 suspensory device, consisting of a stem 6 which fits revolvably in the tubular member 4', and having the angularly disposed arms 7 and 8 at the respective ends thereof. Numerical 9 denotes the prong, one end of which terminates in a sharp point 9'. The other end of the prong 9 is integrally united with the free end of the arm 7 by means of the coil spring 10, whereby the prong 9 is normally and resiliently retained in substantially the 70 position in which it is shown in Fig. 2. The free end of the arm 8 carries the catch 11, which is adapted to receive the pointed end portion of the prong 9, whereby the point 9' may be fully enclosed and protected, as 75 shown in Fig. 1.

The snap fastener comprises the male member 12, and the female member 13. The male member has a stud 12' projecting outward centrally thereof, while the female 85 member has a socket 13' formed concentrically therein and opening inwardly, to receive the stud 12' therein by compression.

Letters C, D and E denote fish-hooks, or angling-hooks, for the carrying and protection of which is the purpose of this invention.

My construction is adapted to contain advertising matter, to be printed thereon, as for instance the words "Izaak Walton 05 Angler", as shown in Fig. 1, which in this instance is more of an identification means, as it may in place thereof be the name of the owner of the packet on which it is 100 printed.

In practice any desired number of fish-hooks may be strung on the prong 9, after which the prong may be sprung up to cause the pointed end 9' to enter the catch 11, after 5 which the member 2 may be folded in upon the hooks, and the member 3 is then folded inward over a portion of the member 2, with the stud 12' contacting with the mouth of the socket 13', then by pressing the member 10 13 toward the member 12 the stud will be driven into the socket, thereby securing the packet in its closed position, as in Fig. 5. To open the packet one has only to pull the members 12 and 13 apart and then open 15 out the members 2 and 3, as in Fig. 3, after which one or more of the hooks C, D and E may be removed from the prong 9, or other hooks may be placed thereon.

It will be apprehended that while this device, as shown and described herein, is very simple and may appear infinitesimal in character, yet it will afford a great amount of satisfaction, and the avoidance of much trouble and irritation, and a high degree of 20 safety, whereby the advantages thereof to the angler will be immensurate and delectable.

I desire that it be understood that various changes may be made in the several details, 25 from that shown and described, without departing from the spirit of the invention and without sacrificing any of the advantages thereof which are new and useful.

Having now fully shown and described 30 my invention, what I claim and desire to secure by Letters Patent of the United States, is—

An angler packet comprising a three-part case with the parts thereof adapted to fold 35 together, a hanger secured across the top of the central portion of said case and forming a tubular portion at its lower edge, a suspensory device comprising a stem rotatable in said tubular portion, arms extending 40 downwardly from the ends of said stem, a prong having one end thereof integrally connected with one of said arms by means of a spring, and a catch carried by the lower end of the other one of said arms and 45 adapted to detachably secure the free end of said prong.

In testimony whereof I have hereunto subscribed my name to this specification.

CLARK J. HAZLITT.
